UNITED STATES PATENT OFFICE.

REINHOLD G. HOUSDORFER, OF DETROIT, MICHIGAN.

AXLE DIES.

Application filed April 21, 1921. Serial No. 463,132.

To all whom it may concern:

Be it known that I, REINHOLD G. Housdorfer, a citizen of the United States of America, residing at Detroit, in the county of Wayne and State of Michigan, have invented certain new and useful Improvements in Axle Dies, of which the following is a specification, reference being had therein to the accompanying drawings.

10 In forming axles with the dies disclosed in my Patent No. 1,050,460, granted Jan. 14, 1913, I had difficulty in preventing the formation of a fin, on the second upset or operation, which, when formed, is hard to remove. To prevent the formation of this fin and make a better axle is the main object of this invention, which is accomplished in part, by dies of novel construction.

Another object of this invention is to form 20 the ends of an axle so that the grain of the metal will be towards the ends of the yoke or fork members so as to resist, as much as possible, breakage of the axle members. This object is attained by constructing the 25 forming apparatus so that when the ends of the axle are upset and formed, the metal is caused to flow in directions which avoid any abrupt bends, thus preserving as much as possible, the tensile strength of the metal so 30 as to resist to a high degree the stresses and strains to which the forks or yokes of the axle may be subjected when forming part of a vehicle.

A further object of my invention is to 35 provide dies for producing an embryoable end with a degree of accuracy that insures a minimum amount of waste, expedite other operations to complete the axle, and as illustrating a preferred embodiment of my invention, I will describe, with the assistance 40 of the accompanying drawings, dies as now practiced by me.

In the drawings,

Figure 1 is a side elevation of an embryo 45 end of an axle bar or blank showing the same as formed by the dies;

Fig. 2 is an end view of dies showing the portions thereof used for the formation of an embryo axle end;

Fig. 3 is a plan of the same;

Fig. 4 is an end view of the dies, and

Fig. 5 is a side elevation of one of the dies showing punches or movable dies relative thereto.

55 To make the axle end by three distinct

operations which may be successively carried on and thus insure an economical and expeditious production, it is necessary to use two dies generally designated A and B and these dies may be movable relative to each other, or the die A considered stationary and the die B as movable. In either instance, the movement is sufficient to permit of a piece of stock, in the form of a bar 7, as shown in Figs. 1, 2 and 3, being placed between the dies. The die A has its upper inner edge 60 provided with a longitudinal recess 8 to receive the bar 7 so that said bar may be clamped in position, with one end of the bar protruding from the dies, when said dies are 65 brought together. At that end of the die A from which the extremity of the bar 7 protrudes the recess 8 is flared or enlarged, as at 9 with an overhanging lip or ledge 10, and this portion of the recess 8 is concave, from 70 the lip or ledge 10 to the body of the die.

The die B extends beyond the die A and has an end thereof recessed, as at 11, in a plane with the recess 8 and pivotally 75 mounted in said recess by a pin 12 or other 80 pivotal means is an upsetting tool or die 13 having a head 14 protruding from the inner face of the die B, adapted to impinge against the protruding end of the bar 7 when the dies A and B are brought together. The tool or die 13 is pivoted intermediate its ends 85 so that its end 15 may abut the die B and limit the outward movement of the head 14, which is maintained normally in its outermost position by a coiled expansion spring 90 16 placed in confronting recesses 17 in the die B and the tool 13. The head 14 of the tool 13 has a concave forming face 18, and assuming that the bar 7 has been placed in the recess 8 of the die A and the die B 95 shifted toward the bar, then the head 14 of the tool impinges against the protruding end of the bar and forces it into the flared end 9 of the recess 8. The protruding end 100 of the bar is therefore disposed at an angle to the clamped portion of the bar 7 and the head 14 of the tool 13 is practically in the axis of said bar. The head 14, which is still 105 in an open or extended position, may now be struck by a punch or blow head 19 and forced inwardly against the angularly disposed end of the bar to upset the same.

In the first part of this operation, when the protruding end of the bar is bent at an angle to the clamped body of the bar, the 110

action of the tool 13 is sustained by its pivot pin and the outer end of the tool bearing against the die. When a blow is delivered on the head 14 to upset the angular end of the bar the tool turns on its pivot and enters the outer end of the recess 8 to the extent of crowding the end of the bar in the end of the recess, so that the outer end of the bar has a shape imparted thereto along the lines suggested in Fig. 1. In this figure it will be observed that the end of the bar is now disposed at an obtuse angle relative to the body of the bar and that at the inner bend the bar has received a rounded surface 20 and that the outer bend a rounded surface 21 which has also been concaved, as at 22, thus reducing the cross sectional area at the bend of the bar, leaving a protuberance 23 that ultimately results in a lower fork member of the axle, when the embryo axle end is subjected to additional operations.

The first operation may be considered as having been performed at the top or in the upper portions of the dies A and B and the additional operations take place between the dies A and B below the location of the first operation.

What I claim is:—

1. Means for partially forming an axle from a blank, comprising dies between which the blank may be held, an instrumentality carried by one of said dies adapted to bend the blank when the dies are brought together and means adapted to impinge against the instrumentality to fur-

ther shape the open end of the blank held by said die.

2. Axle forming means comprising dies adapted to hold a blank therebetween, and means adapted to reduce the end of the blank between the dies, said means including an instrumentality which assumes the position alining with said blank to cause a reduction at one side of the axis of the blank. 45

3. Axle forming means as in claim 2, characterized by the instrumentality being disposed to bend the blank prior to reducing the end thereof.

4. Axle forming means as in claim 2, 50 characterized by the instrumentality having a configuration to form an embryo fork.

5. Means for forming an axle, comprising dies between which a blank may be held, said dies having the confronting faces there of provided with recesses into which the blank extends, one of the recesses having a flared end, and a tool in opposed relation to the flared end of the die recesses, said tool having a configuration which co-oper- 55 ates with the flared end of the die recess in imparting an embryo fork shape to the end of the blank. 60

In testimony whereof I affixed my signature in presence of two witnesses.

REINHOLD G. HOUSDORFER.
